United States Patent Office

Des. 199,693
Patented Dec. 1, 1964

199,693

COMBINED WEIGHING SCALE AND TICKET COUNTER

Albert Hohmann, Brooklyn, N.Y., assignor to American
Electronics, Inc., Fullerton, Calif., a corporation of
California

Filed Dec. 12, 1961, Ser. No. 67,885

Term of patent 14 years

(Cl. D52—10)

FIG. 1

FIG. 2

FIG. 3

FIG. 4

FIG. 5

FIG. 6.

FIGURE 1 is a plan view of a combined weighing scale and ticket counter, showing my new design.

FIGURE 2 is a front elevational view thereof.

FIGURE 3 is a side elevation thereof as viewed from the left side of FIGURE 2.

FIGURE 4 is a side elevation thereof as viewed from the right side of FIGURE 2.

FIGURE 5 is a rear elevational view thereof.

FIGURE 6 is a rear perspective view thereof.

I claim:

The ornamental design for a combined weighing scale and ticket counter, substantially as shown.
